(57) **CLAIM**

I claim the ornamental design for a heavy equipment plank,
as shown and described.

DESCRIPTION

FIG. 1 shows a perspective side view of the invention;
FIG. 2 shows a straight side view thereof;
FIG. 3 shows a top view thereof;
FIG. 4 shows the straight front view thereof; and,
FIG. 5 shows close up corner view thereof.
The unit is symmetric, the front and back are the same along
with the right and left sides and top and bottom.
The broken lines in FIG. 5 represents a cut out close up and
forms no part of the claimed design.
